UNITED STATES PATENT OFFICE.

FERDINAND ERNEST LAMMERT, OF CHICAGO, ILLINOIS.

GAS PURIFIER.

Application filed June 24, 1924. Serial No. 722,119.

My invention relates to an air purifying apparatus attached to the discharge end of an air compressor or air vacuum pump to free the air as completely as possible from oil vapors or other foul matter as the air comes from the compressor or exhaust machine.

The object of the invention is to produce a neat, compact, cheap and highly efficient apparatus that may be readily attached to the vacuum or compressor machines generally employed.

Reference will be had to the accompanying drawing in which Fig. 1 is a front elevation of what may be either an air exhaust machine or an air compressor of the rotary type to which my apparatus is attached.

Figure 2 is a vertical section through the air purifying apparatus to which this invention relates.

Figure 3 is a transverse section on line 3—3 of Fig. 2.

Figure 4 is a detail sectional elevation showing the water pipe connection.

Figure 5 is an end view indicated by the line 5—5 of Fig. 2.

In the drawing 1 indicates the body of an ordinary rotary air compressor or exhaust machine which is here shown driven by a shaft 2 by a belt drive pulley 3 or may be driven by any suitable means.

The exhaust or discharge from the rotary compressor 1 passes out by a pipe 4 from the machine 1. The pipe 4 enters into the chamber 5 in which there is provided a series of baffles and other means for collecting oil and other impurities that may come along with the air as it leaves the machine 1.

Air compressor and exhaust machines of the rotary positive type such as is here shown are necessarily well lubricated and there is carried along with the air more or less lubricating oil from the vanes of the machine. The heavy globules of oil and other heavy impurities are usually segregated in the chamber 5 and are returned back to the machine 1 for continued repeated use. Various different oil catching devices are used in this chamber 5.

In spite of the different baffles and other means employed in the chamber 5 for catching the oil and freeing the air from it some oil goes over and through the chamber 5 in the form of finely divided spray or vapor.

The accumulation of oil vapor in the air of a machine of this class is promoted by the

heat of the compression that is given the air in passing through the machine 1 as the air will take on more oil vapor, or any other vapor for that matter, as its temperature rises. With the oil separating devices commonly used in what corresponds to the chamber 5 there is relatively a large amount of oil vapor passing on through with the air to become a troublesome feature of condensation and pollution of the air discharged by the machine. It is highly desirable to eliminate the oil vapor from the air as much as possible. Not only to do that, but to do it in a neat efficient way and in compact form.

Many of these machines are used in close quarters by unskilled help. For illustration with milking machines placed in barns and other places and installed and used by help not generally familiar with machinery.

It is desirable to make equipment of this kind as much as possible in the form of a single unit as it is shipped from the factory and eliminate as much as possible any labor setting up and adjusting it after the machine reaches its place of service. To this end I have provided a compact and efficient device that may be connected and sent out with the machine itself.

On the top of the ordinary chamber 5 I provide an additional chamber 6 in which to contain my purifying devices. After the air passes through my chamber 6 as I will describe it is then discharged through the pipe 7 to the service or to the outside air depending on whether the machine is used as a compressor or as an exhaust.

While the heavier particles of the oil will be gathered in the chamber 5 some remains in vapor which residual oil is collected from the permanent gases in my chamber 6 and likewise returned to be used over again.

The chamber 6 is provided with a bottom plate wall 8 secured by bolts or any suitable means to the flange 9 of the top of the chamber 5 and thus as it were my purifier is an addition to the nominal oil separator chamber 5. At the top of the chamber 6 I provide the flange plate 10 into which the discharge pipe 7 is secured and this flange plate 10 is secured by bolts or other suitable means to the body of the chamber 6.

On the interior of the chamber 6 I provide a horizontal wall 11 located below the flange plate 10 providing the annular space 13, and a horizontal wall 12 located sufficiently above the bottom plate wall 8 to provide annular

space 14 and these spaces are connected by tubes 15 somewhat after the manner of a tubular boiler arrangement.

The arrangement of these tubes is shown 5 in Figs. 3 and 5 and are staggered in their relationship similar to boiler construction fashion and the circulating water is made to enter into the pipe 16 and discharge out of the pipe 17 and thus be made to circulate around 10 through the tubes 15 and cool the same as well to cool the walls 11 and 12.

The entry of the air from the machine 1 to the chamber 6 is provided by the aperture 18 see Figs. 2 and 3 as it goes up from the chamber 15 5 and it then passes out through the triangular shaped opening 19 inside a cylindrical chamber made by the wall 20 which is divided by an inclined partition wall 21.

The air that comes up from the bottom 20 passes out through the triangular shaped opening 19 as indicated by the arrow 22 and then it passes around between the tubes as indicated by the arrows making a complete circuit of the inside of the chamber 6 and 25 then passes in through a triangular aperture 23 up into the discharge passageway which leads to the pipe 7 see Fig. 2. Thus the air more or less heated from the compressor or 30 exhaust machine 1 after having been relieved of the heavier portion of its oil in the chamber 5 passes around through the cooling purifying chamber 6 where it encounters the various different baffles in the form of the arrangement of the tubes 15 which collects the 35 oil by the cooling effect upon the air and by the changes in direction of the air current. The changes of direction of the air current in passing through the chamber 6 and around the tubes 15 are assisted by baffles 24 on the 40 inner side of the outer wall of the chamber 6 and baffles 25 on the outside of the wall 20. The oil thus collected falls to the lower portion of the chamber 5 and is returned to the machine 1 by pipe 26 Figs. 3 and 5.

45 The circulating water pipes 16 and 17 as described are connected up to the water system that cools the machine 1 through the medium of the pipe 28.

More or less dust, comptar, or other foul 50 products are segregated from the air by my purifier and does accumulate to some extent on the tubes 15 and onto the horizontal wall tube sheets 11 and 12 and to facilitate the cleaning of the same I provide the hand hole 55 covers or detachable sections 29 secured by the bolts 30 to the main body of the chamber 6.

Thus by removing these sections of the 60 chamber access may be had to clean the inside of the chamber 6.

This apparatus is cheaply constructed since the chamber 6 with its walls may be cast in one body block. The hand hole pieces 29 and 65 the top and bottom plates 8 and 10 are made separately and fitted on to the block 6. The

tubes 15 being fitted in before the plates 8 are in place, and the whole is then secured to the chamber 5 and shipped as a part of the machine 1 which is a desideratum.

The arrangement of the interior of the 70 chamber 6 by means of the partition wall 21 is an efficient manner for diverting the stream of oil vapor laden air around through the purifier and delivering it back in the normal line of the exhaust or discharge pipe 7 75 so that this apparatus may be attached to installations previously put out without necessarily having to change materially the location of the piping system previously used which is a desideratum. 80

What I claim is:

1. In a gas purifier, the combination with an annular cooling chamber, of a concentric flue within said chamber having lateral openings into said chamber, an inclined partition 85 axially closing said flue and also extending across said cooling chamber at one side of said flue, a plurality of tubes in said chamber opening outwardly through the annular end walls of said chamber, and a plurality of deflecting baffles extending inwardly from the lateral walls of said chamber. 90

2. In a gas purifier, the combination with an annular cooling chamber, an annular wall at each end of said chamber having tube receiving openings, a plurality of tubes joining said annular walls, a central flue having an inclined partition and openings through the walls thereof and communicating with said cooling chamber on opposite sides of said partition, and means for withdrawing separated matter. 95

3. In an apparatus of the class described, an integrally cast block having terminal tube sheets, a centrally located cylindrical flue divided by an inclined partition wall and said cylindrical flue provided with triangular apertures located on either side of the inclined partition wall, a top covering plate and a bottom covering plate secured to projecting portions of the outer walls of the said block 105 in a manner to provide circulating spaces on the outside of each of the tube sheets. 110

4. In an apparatus of the class described, a vertically arranged discharge flue divided by an inclined wall and a cooling chamber located outside of and around the vertically arranged discharge flue and said cooling chamber provided with a series of tubes adapted to carry a circulating cooling 120 medium, the said tubes opening at each end into a common cooling medium chamber and means for directing the travel of the discharge air up against the inclined partition wall and around annularly through the cooling chamber and back against the inclined partition wall and thence to the final discharge orifice. 125

5. In a gas purifier, the combination with a central flue provided with lateral openings, 130

of a concentric annular cooling chamber with which said lateral openings communicate, an annular cooling medium chamber also concentric with said flue at each end of said cooling chamber, a plurality of tubes passing through said cooling chamber and connecting said annular cooling medium chambers, a plurality of partitions in said cooling medium chambers for controlling the direction of flow

of fluid through said tubes, and an inclined 10 partition wall axially closing said flue and also extended laterally into said cooling chamber.

Signed at Chicago, in the county of Cook and State of Illinois, this 21st day of June, 15 1924.

FERDINAND ERNEST LAMMERT.
